COAXIAL TRANSMISSION LINE

Hugh E. Reppert, San Diego, Calif.

Application October 1, 1940, Serial No. 359,228

14 Claims. (Cl. 174—21)

(Granted under the act of March 3, 1883, as
amended April 30, 1928; 370 O. G. 757)

My invention relates to a coaxial transmission line and more particularly to a sectionalized transmission line of the stated character.

As is well known, coaxial transmission lines are employed for transmitting radio frequency energy because of the many structural and electrical advantages inherent therein. Among the advantages possessed by coaxial transmission lines are the maintenance by the same of substantially uniform electrical characteristics under all service conditions and the ability to increase the power transmission thereof by the introduction of gas under pressure between the outer and inner concentric conductors.

Where it becomes necessary to employ a sectionalized coaxial transmission line it is essential to retain the above enumerated advantages even where the sections for any reason must be relatively movable. The foregoing desirable result is achieved by the present invention through the provision of a sectionalized coaxial transmission line in which the sections are relatively movable and sealed one to the other while maintaining electrical continuity therebetween.

In the preferred embodiment of the present invention the sectionalized coaxial transmission line is comprised of a plurality of relatively movable sections, one of which includes a pair of insulatingly spaced concentric conductors and another of which includes a pair of insulatingly spaced concentric conductors electrically continuous with the first mentioned pair. Means is provided for sealing one transmission line section to another, the said means including a pair of concentric relatively movable sleeves secured to the outer conductors of the respective conductor pairs and held in rotative fluid-tight relation.

While in the preferred embodiment of the present invention gas is maintained under pressure between the outer and inner concentric conductors of the transmission line sections and is prevented from escaping by the sealing means, it is within the purview of the present invention to employ instead a dry gas at atmospheric pressure. In the latter case the sealing means prevents the ingress of extraneous moisture or other fluids that would tend to alter the electrical characteristics of the transmission line and for this purpose includes a resilient convoluted member associated with the sleeves to assist in maintaining a fluid-tight relation therebetween. Where the gas is under pressure, however, the resilient member is preferably retained but is not essential since the pressure of the confined gas alone may be employed to assist in maintain-

ing the desired fluid-tight relation between the relatively movable sleeves.

In the light of the foregoing, it is among the principal objects of my invention to provide a sealed sectionalized coaxial transmission line in which the sections are relatively movable and electrically continuous; to provide a transmission line of the stated character in which the electrical line of the stated character in which the electrical connections between the sections and other interior parts of the latter are sealed against access of extraneous fluids; and to provide a transmission line of the character above noted employing gas under pressure in which the pressure of the confined gas assists in maintaining a fluid-tight seal between the sections thereof.

Other objects and many of the attendant advantages of this invention will be readily appreciated as the same becomes better understood by reference to the following detailed description when considered in connection with the accompanying sheets of drawings, wherein:

Fig. 1 is a central longitudinal sectional view of one embodiment of the sectionalized transmission line of the present invention in which the sections thereof are sealed one to the other by relatively movable sleeves in fluid-tight engagement at their conical bearing surfaces;

Fig. 2 is bottom plan view of the sectionalized transmission line of Fig. 1 showing, among other things, the construction of one of the spacing insulators;

Fig. 3 shows the sectionalized transmission line of Fig. 1 as used with a directive loop antenna.

Fig. 4 is a central longitudinal sectional view of a still further embodiment of the sectionalized transmission line of the present invention wherein a flexible flanged cylindrical member is employed for effecting a seal between the relatively movable sleeves; and

Fig. 5 is a perspective view of the flanged cylindrical sealing member employed in the embodiment of Fig. 4.

Turning now to the drawings, there is shown in Figs. 1 and 2 thereof a sectionalized coaxial transmission line comprised of a plurality of relatively movable sections, one of which includes a pair of insulatingly spaced concentric electrical conductors 1 and 2 and another of which includes a pair of insulatingly spaced concentric electrical conductors 3 and 4 electrically continuous with the first mentioned pair. Insulators 5 fabricated of any suitable material are employed to maintain the inner conductors 2 and 4 spaced and electrically insulated from the outer concentric con-

ductors 1 and 3, the insulators being shown by way of example as peripherally serrated to permit the passage of gas along and between the transmission line sections as clearly indicated in Fig. 2.

The inner conductors 2 and 4 and the outer conductors 1 and 3 of the respective sections are electrically and detachably connected in any suitable manner. Thus, the inner conductor 2 is shown by way of illustration as provided with an integral male contact member 6 slidably engaging the walls of a recessed female contact member 7 integral with the inner conductor 4 in a manner to establish electrical continuity between these conductors in all rotative positions of adjustment of the transmission line sections.

One of the pair of relatively movable sleeves is conveniently, although not necessarily, employed for electrically interconnecting the outer conductors 1 and 3 of the respective sections. Thus, as clearly shown in the drawings, the inner sleeve 8 is fabricated of some suitable electrically conductive material and is secured to the outer conductor 3 in a fluid-tight and electrically continuous manner. The sleeve 8 is provided with a cylindrical extension 9 that serves as a female contact member and receives in sliding engagement therewith the slotted terminal portion 10 of the outer conductor 1. The terminal portion 10 serves as a male contact member which by virtue of its resilient slotted construction and its tight fit is maintained in intimate electrical contact with the inner wall surface of the cylindrical extension 9 in all rotative positions of adjustment of the transmission line sections.

For sealing one transmission line section to the other, there is provided a pair of relatively movable sleeves 8 and 11 secured to the outer conductors 3 and 1 of the respective conductor pairs and having complementary conical bearing surfaces 12 and 13 respectively. A flange 14 is affixed to the outer conductor 1 in a fluid-tight manner and has detachably secured and sealed thereto the outer sleeve 11 by means of the screws 15 and the intervening gasket 16. Where the transmission line section comprised of the conductors 1 and 2 is to be movable the flange 14 may be provided with the cylindrical member 17 secured thereto by the screws 18 for facilitating the rotation of the same. By detachably connecting the outer sleeve 11 and flange 14 it is possible to disconnect and disassemble the transmission line sections when this becomes necessary or is desired.

To assist in maintaining an effective fluid-tight seal at the complementary conical bearing surfaces 12 and 13 of the sleeves and to reduce to a minimum any friction between the relatively movable surfaces of the sleeves 8 and 11, the inner sleeve 8 is provided with a series of annular grooves 19 for receiving a suitable lubricant of proper viscosity which may be conveniently chosen as a heavy oil. The grooves 19 are machined sufficiently deep so that they may initially receive a quantity of lubricant to provide a reserve supply thereof. The lubricant spreads in a thin film between the juxtaposed surfaces of the sleeves 8 and 11 and not only reduces the rotational frictional losses to a minimum but also assists in maintaining an effective fluid-tight seal at the conical bearing surfaces 12 and 13.

When using a dry inert gas at atmospheric pressure between the outer conductors 1 and 3 and the inner concentric conductors 2 and 4 of the transmission line sections, a convoluted resilient member 20 of the compressional type is

employed for maintaining the conical bearing surfaces 12 and 13 of the sleeves in wedging but rotative fluid-tight engagement. The compression spring 20 has secured thereto in any suitable manner the bearing rings 21 and 22 which engage complementary bearing surfaces 23 and 24 on the flange 14 and on the terminal portion of the sleeve 8 respectively. By disposing the spring 20 in the manner depicted in the drawings, the sleeves 8 and 11 are urged in opposite directions to maintain the complementary conical bearing surfaces 12 and 13 of the sleeves 8 and 11 respectively in juxtaposed relation and thus effect a seal between the transmission line sections.

Where a dry inert gas above atmospheric pressure, as nitrogen for example, is disposed between the outer conductors 1 and 3 and the inner concentric conductors 2 and 4, as in the embodiment depicted in Fig. 1, the compression spring 20 may be dispensed with if desired, since the sleeves 8 and 11 will be urged in opposite directions to maintain the conical bearing surfaces 12 and 13 in wedging but rotative fluid-tight engagement by the pressure of the confined gas alone. This follows from the fact that the gas pressure within the spring chamber 25 is substantially identical with that obtaining between the outer conductors 1 and 3 and the inner conductors 2 and 4 of the transmission line sections because of the gas leakage between the outer contact members 9 and 10. While in most cases the pressure of the gas within the transmission line sections will be sufficiently in excess of that of the circumambient atmosphere to alone maintain an effective fluid-tight seal at the conical bearing surfaces 12 and 13 of the sleeves, it is preferred to retain the spring 20 so that the seal at the conical bearing surfaces 12 and 13 may not be broken if for any reason the gas pressure within the transmission line should be disturbed.

Fig. 3 shows the sectionalized transmission line of Fig. 1 as used with a directive loop antenna. The cylindrical member 17 for facilitating rotation of the upper transmission line section connected to the loop antenna 26 is rotatably supported from the stationary base 27 in any suitable manner. The handwheel 28 secured to the cylindrical member 17 provides a ready means for imparting the desired rotation to the antenna. The lower stationary transmission line section has an electrical terminal 29 secured to the outer conductor 3 in a gas-tight and electrically continuous manner, the inner concentric conductor of this section being provided with the electrical terminal 30. The terminals 29 and 30 are electrically insulated from each other by sleeve 31 of any suitable insulating material the sleeve being sealed in a gas-tight manner to both of the terminals. By means of the terminals 29 and 30 it thus becomes possible to either transmit or receive electrical energy to or from the directive antenna 26. A self-closing valve 32 of any known prior art construction provides a means for filling all sections of the transmission line with a gas or mixture of gases at any desired pressure, the pressure being indicated by any suitable gauge 33.

Turning now to Figs. 4 and 5 of the drawings there is shown a still further embodiment of the sectionalized coaxial transmission line of the present invention likewise comprised of a plurality of relatively movable sections, one of which includes a pair of insulatingly spaced concentric electrical conductors 34 and 35 and another of which includes a pair of insulatingly spaced concentric electrical conductors 36 and 37 electrici-

cally continuous with the first mentioned pair. Insulators 38 fabricated of any suitable material are employed for maintaining the inner conductors 35 and 37 spaced and electrically insulated from the outer conductors 34 and 36, the insulators 38 being provided with irregular peripheral portions to permit the passage of gas along and between the transmission line sections.

The inner conductors 35 and 37 and the outer conductors 34 and 36 of the respective sections are electrically and detachably connected in any suitable manner as in the previous embodiment. Thus the inner conductor 35 is shown by way of example as provided with a male contact member 39 electrically continuous therewith and slidably engaging the walls of a recessed female contact member 40 likewise electrically continuous with the inner conductor 37 in a manner to establish electrical continuity between the conductors 35 and 37 in all rotative positions of adjustment of the transmission line sections.

One of the pair of relatively movable sleeves may again be conveniently employed for electrically interconnecting the outer conductors 34 and 36 of the respective transmission line sections. As clearly indicated in the drawings the inner sleeve 41 fabricated of some suitable electrically conductive material is secured at one of its ends to the outer conductor 34 in a fluid-tight and electrically continuous manner. At its remaining end the sleeve 41 is provided with a cylindrical slotted extension 42 that serves as the female contact member and receives within its confines in sliding engagement therewith the terminal portion 43 of the outer conductor 36 that serves as the male contact member. The male contact member 43 by virtue of its tight fit within the resilient cylindrical slotted extension 42 is maintained in intimate electrical contact with the inner wall surface thereof in all rotative positions of adjustment of the transmission line sections. An annular pad 44 of any suitable material impregnated with a proper lubricant may be optionally employed to reduce the friction between the outer contact members 42 and 43.

For sealing one transmission line section to the other there is provided, among other things, a pair of relatively movable sleeves 41 and 45 secured to the outer conductors 34 and 36 of the respective conductor pairs and having complementary bearing surfaces 46 and 47 respectively. Between the bearing surfaces 46 and 47 there is interposed for cooperation therewith a well lubricated thrust bearing comprised of the ball bearings 48 and the annular thrust plates 49 and 50 to take up the thrust exerted by the sleeve 41 against the sleeve 45 while permitting free rotative movement therebetween.

A flange 51 is affixed to the outer conductor 36 in a fluid-tight manner and has detachably secured and sealed thereto the outer sleeve 45 by means of the screws 52 and the intervening gasket 53. Where the transmission line section comprised of the conductors 36 and 37 is to be movable the flange 51 may be provided with the cylindrical member 54 secured thereto by the screws 55 for facilitating the rotation of the same. By detachably connecting the outer sleeve 45 and flange 51 it is possible, as in the previous embodiment, to disconnect and disassemble the transmission line sections when this either becomes necessary or is desired. To reduce the friction between the juxtaposed surfaces of the relatively movable sleeves 41 and 45 to a minimum, a recessed portion 56 of the outer sleeve

45 is provided with a lubricated packing 57 that is maintained in position by the gland 58 adjustable by the nut 59 in threaded engagement with the sleeve 45. The lubricated packing 57 insures the provision of a thin film of lubricant between the juxtaposed sleeve surfaces so that one sleeve may at all times rotate freely with respect to the other sleeve.

For sealing one sleeve to the other a flanged cylindrical member identified in general by the reference character 60 (Fig. 5) is provided and disposed intermediate the sleeves 41 and 45 as clearly indicated in Fig. 4. The member 60 is fabricated of any suitable fluid impervious material which may for example be fibrous or metallic in character; and the cylindrical wall 61 thereof is rendered flexible in any suitable manner as by tapering the wall thickness thereof to a thin edge as indicated in the drawings. The flange 62 of the cylindrical member 60 is in fluid-tight engagement with the terminal surface 63 of the inner sleeve 41 while the flexible cylindrical wall 61 thereof, by reason of its close fit and resilience, is in fluid-tight engagement with the inner wall surface 64 of the outer sleeve 45. The flange 62 of the cylindrical member 60 may, if desired, be cemented or otherwise secured to the terminal surface 63 of the sleeve 41 to thus rotate with the sleeve and further enhance the fluid-tight seal subsisting therebetween.

When employing a dry inert gas at atmospheric pressure between the outer conductors 34 and 36 and the inner conductors 35 and 37 of the transmission line sections, a convoluted resilient member 65 of the compression type is employed for insuring the maintenance of the flange 62 of the cylindrical member 60 in fluid-tight engagement with the terminal surface 63 of the sleeve 41, the thrust exerted by the compression spring 65 being taken up by the thrust bearing previously described herein. The compression spring 65 has secured thereto in any suitable manner the bearing rings 66 and 67 which engage respectively a complementary bearing surface 68 (Fig. 5) on the flange 62 integral with the cylindrical member 60 and the complementary bearing surface 69 on the flange 51 affixed to the outer conductor 36.

Where dry inert gas above atmospheric pressure is disposed between the outer conductors 34 and 36 and the inner concentric conductors 35 and 37 of the transmission line sections as in the embodiment depicted in Fig. 4, the compression spring 65 may be dispensed with if desired, since the flange 62 and flexible cylindrical wall 61 of the member 60 will be maintained in fluid-tight engagement with the respective surfaces 63 and 64 of the inner and outer sleeves 41 and 45 by the pressure of the confined gas alone, the seal between the cylindrical wall 61 and its cooperating surface 64 being thereby enhanced. This follows from the fact that the gas pressure within the spring chamber 70 is substantially identical with that obtaining between the outer conductors 34 and 36 and the inner conductors 35 and 37 of the transmission line sections because of the gas leakage between the outer contact members 42 and 43. It is this gas pressure within the spring chamber 70 that exerts a flexing action on the cylindrical wall 61 of the member 60 and a thrusting action on the flange 62 thereof that is taken up by the thrust bearing, which together effect and insure a fluid-tight seal between the flanged cylin-

drical member 60 and the relatively movable sleeves 41 and 45. While in most cases the pressure of the gas within the transmission line sections will be sufficiently in excess of that of the circumambient atmosphere to alone maintain an effective fluid-tight seal as described, it is preferred to retain the compression springs 65 so that the seal between the flange 62 of the cylindrical member 60 and the terminal surface 63 of the sleeve 41 may not be broken if for any reason the gas pressure within the transmission line should be disturbed.

From the foregoing it should be clear that the means depicted in Figs. 1 and 4 for sealing one transmission line section to another prevents the escape of any gas under pressure. If, on the other hand, dry gas at atmospheric pressure is employed between the outer and inner concentric conductors of the transmission line sections, the sealing means prevents the ingress of extraneous moisture or other fluids that would tend to alter the electrical characteristics of the transmission line. In this connection, it should be observed that the inner and outer contact members electrically interconnecting the transmission line sections are fully protected against access of extraneous fluids that might tend to impair the low resistance contact therebetween.

According to the provisions of the patent statutes, I have set forth the principle and mode of operation of my invention and have illustrated and described what I now consider to represent its best embodiments. However, I desire to have it understood that within the scope of the appended claims the invention may be practiced otherwise than as specifically illustrated and described.

The invention herein described and claimed may be used and manufactured by or for the Government of the United States of America for governmental purposes without the payment of any royalties thereon or therefor.

I claim:

1. A sectionalized coaxial transmission line comprising in combination a pair of inner relatively movable electrically connected conductors, a pair of outer relatively movable electrically connected conductors concentric with and insulatingly spaced from the first mentioned pair of conductors, a gas under pressure between the inner and outer conductor pairs, a pair of relatively movable sleeves provided with complementary bearing surfaces, one of said sleeves being secured to one of said outer conductors, the other of said sleeves being secured to the other of said outer conductors in concentric relation and interior engagement with the first mentioned sleeve, the second mentioned sleeve extending from the outer conductor secured thereto to slidably engage the juxtaposed end of the remaining outer conductor for establishing electrical continuity therebetween and the sleeves being associated in a fluid-tight manner to prevent the escape of the aforesaid gas, a convoluted resilient member associated with said sleeves, the said member and the pressure of the aforementioned gas being operative to maintain complementary bearing surfaces of the sleeves in juxtaposed relation.

2. A sectionalized coaxial transmission line comprising in combination a pair of inner relatively rotatable electrically connected conductors, a pair of outer relatively rotatable electrically connected conductors concentric with and insu-

latingly spaced from the first mentioned pair of conductors, a pair of relatively rotatable sleeves, one of said sleeves being secured to one of said outer conductors, the other of said sleeves being secured to the other of said outer conductors in concentric relation and interior engagement with the first mentioned sleeve, the second mentioned sleeve extending from the outer conductor secured thereto to slidably engage the juxtaposed end of the remaining outer conductor for establishing electrical continuity therebetween.

3. A sectionalized coaxial transmission line comprising in combination a first pair of insulatingly spaced concentric conductors, a second pair of insulatingly spaced concentric conductors arranged for connection with said first mentioned pair, means for establishing electrical connections between the inner and outer conductors of the respective conductor pairs and means for sealing the electrical connections against access of extraneous fluids, the said pairs of conductors being relatively rotatable.

4. A sectionalized coaxial transmission line comprising in combination a plurality of relatively rotatable sections, one of said sections including a pair of insulatingly spaced concentric conductors, another of said sections including a pair of insulatingly spaced concentric conductors arranged for connection with said first mentioned pair, means including relatively movable parts for establishing electrical connections between the inner and outer conductors of the respective conductor pairs, and means for sealing the electrical connections against access of extraneous fluids, said last mentioned means including a pair of concentric relatively rotatable sleeves secured to the outer conductors of the respective conductor pairs.

5. A sectionalized coaxial transmission line comprising in combination a plurality of relatively movable sections, one of said sections including a pair of insulatingly spaced concentric conductors, another of said sections including a pair of insulatingly spaced concentric conductors arranged for connection with said first mentioned pair, means including relatively movable parts for establishing electrical connections between the inner and outer conductors of the respective conductor pairs, a pair of concentric relatively movable sleeves secured to the outer conductors of the respective conductor pairs, and a convoluted resilient member disposed intermediate said sleeves, the said member being operative to maintain complementary bearing surfaces of the sleeves in juxtaposed relation.

6. A sectionalized coaxial transmission line comprising in combination a plurality of relatively movable sections, one of said sections including a pair of insulatingly spaced concentric conductors, another of said sections including a pair of insulatingly spaced concentric conductors electrically connected with said first mentioned pair, a pair of concentric relatively movable sleeves secured to the outer conductors of the respective conductor pairs, one of said sleeves extending from the outer conductor secured thereto to slidably engage the juxtaposed end of the other outer conductor for establishing electrical continuity therebetween, and a convoluted resilient member associated with said sleeves, the said member being operative to maintain complementary bearing surfaces of the sleeves in juxtaposed relation.

7. A sectionalized coaxial transmission line

comprising in combination a plurality of relatively movable sections, one of said sections including a pair of insulatingly spaced concentric conductors, another of said sections including a pair of insulatingly spaced concentric conductors electrically connected with said first mentioned pair, a pair of concentric relatively movable sleeves provided with complementary conical bearing surfaces secured to the outer conductors of the respective conductor pairs, and a convoluted resilient member associated with said sleeves, the said member being operative to maintain the conical bearing surfaces of the sleeves in wedging fluid-tight engagement.

8. A sectionalized coaxial transmission line comprising in combination a plurality of relatively movable sections, one of said sections including a pair of insulatingly spaced concentric conductors, another of said sections including a pair of insulatingly spaced concentric conductors electrically connected with said first mentioned pair, a pair of concentric relatively movable sleeves provided with complementary conical bearing surfaces, one of said sleeves being secured to the outer conductor of one of the conductor pairs and extending therefrom to slidably engage the juxtaposed end of the other outer conductor of the other conductor pair and the remaining sleeve being removably secured to the last mentioned outer conductor of the other conductor pair, and a convoluted resilient member disposed intermediate said sleeves, the said member being operative to maintain the conical bearing surfaces of the sleeves in wedging fluid-tight engagement.

9. A sectionalized coaxial transmission line comprising in combination a plurality of relatively movable sections, one of said sections including a pair of insulatingly spaced concentric conductors, another of said sections including a pair of insulatingly spaced concentric conductors electrically connected with said first mentioned pair, a gas under pressure between the inner and outer conductors of the conductor pairs, and a pair of concentric relatively movable sleeves provided with complementary conical bearing surfaces secured to the outer conductors of the respective conductor pairs, the conical bearing surfaces of the sleeves being maintained in wedging fluid-tight engagement by the pressure of the confined gas.

10. A sectionalized coaxial transmission line comprising in combination a plurality of relatively rotatable sections, one of said sections including a pair of insulatingly spaced concentric conductors, another of said sections including a pair of insulatingly spaced concentric conductors electrically continuous with said first mentioned pair, a pair of concentric relatively rotatable sleeves secured to the outer conductors of the respective conductor pairs and a member disposed intermediate said sleeves and in sealing engagement therewith.

11. A sectionalized coaxial transmission line comprising in combination a plurality of relatively movable sections, one of said sections in-

cluding a pair of insulatingly spaced concentric conductors, another of said sections including a pair of insulatingly spaced concentric conductors electrically continuous with said first mentioned pair, a pair of superposed concentric relatively movable sleeves secured to the outer conductors of the respective conductor pairs, a flexible cylindrical member provided with a flange disposed intermediate said sleeves, the flange of said member being in fluid-tight engagement with one of said sleeves and the flexible cylindrical wall thereof being in fluid-tight engagement with the other of said sleeves, whereby to effectually seal one transmission line section to another.

12. A sectionalized coaxial transmission line comprising in combination a plurality of relatively movable sections, one of said sections including a pair of insulatingly spaced concentric conductors, another of said sections including a pair of insulatingly spaced concentric conductors electrically continuous with said first mentioned pair, a gas under pressure between the inner and outer conductors of the conductor pairs, a pair of superposed concentric relatively movable sleeves secured to the outer conductors of the respective conductor pairs, a flexible cylindrical member provided with a flange disposed intermediate said sleeves, a convoluted resilient member likewise disposed intermediate said sleeves and exerting a force against the flange of the cylindrical member, the flange of the cylindrical member being thereby held in fluid-tight engagement with one of said sleeves and the flexible cylindrical wall thereof being held in fluid-tight engagement with the other of said sleeves by the pressure of the aforesaid gas, whereby to effectually seal one transmission line section to another.

13. A sectionalized coaxial transmission line comprising in combination a plurality of relatively rotatable sections, one of said sections including a pair of insulatingly spaced concentric conductors, another of said sections including a pair of insulatingly spaced concentric conductors electrically continuous with said first mentioned pair, and means for sealing one relatively rotatable transmission line section to another.

14. A sectionalized coaxial transmission line comprising in combination a plurality of relatively movable sections, one of said sections including a pair of insulatingly spaced concentric conductors, another of said sections including a pair of insulatingly spaced concentric conductors electrically continuous with said first mentioned pair, a gas under pressure between the inner and outer conductors of the conductor pairs, and means for sealing one transmission line section to another, said means including a pair of concentric relatively movable sleeves secured to the outer conductors of the respective conductor pairs and held in fluid-tight relation by the pressure of the confined gas.

HUGH E. REPPERT.
